Patented Sept. 1, 1959

186,025

COMBINED TABLE AND HI-FIDELITY CABINET

Robert E. Fisher, Minneapolis, Minn.

Application June 9, 1958, Serial No. 51,247

Term of patent 3½ years

(Cl. D33—14)

Figure 1 is a perspective view of a combined table and hi-fidelity cabinet showing my new design.

Figure 2 is a front view thereof.

Figure 3 is a rear view thereof.

Figure 4 is an end view thereof.

Figure 5 is an end view opposite to that of Figure 4.

I claim:

The ornamental design for a combined table and hi-fidelity cabinet, as shown.
